(57) **CLAIM**

The ornamental design for a plant pot assembly, as shown and described.

DESCRIPTION

FIG. 1 is a front perspective view of a plant pot assembly, according to the present invention;

FIG. 2 is a front elevation view of the plant pot assembly of FIG. 1;

FIG. 3 is a rear elevation view of the plant pot assembly of FIG. 1;

FIG. 4 is a left side elevation view of the plant pot assembly of FIG. 1;

FIG. 5 is a right side elevation view of the plant pot assembly of FIG. 1;

FIG. 6 is a top view of the plant pot assembly of FIG. 1;

FIG. 7 is a bottom view of the plant pot assembly of FIG. 1;

FIG. 8 is a front top right perspective view of the plant pot assembly of FIG. 1;

FIG. 9 is a front bottom left perspective view of the plant pot assembly of FIG. 1; and

FIG. 10 is an exploded elevation view showing the inner element and the outer element of the plant pot of assembly FIG. 1;

FIG. 11 is a bottom right front perspective view of the inner element of the plant pot assembly of FIG. 1;

FIG. 12 is a bottom view of the inner element of the plant pot assembly of FIG. 1;

FIG. 13 is a top front perspective view of the inner element of the plant pot assembly of FIG. 1;

FIG. 14 is a bottom right front perspective view of the outer element of the plant pot assembly of FIG. 1;

FIG. 15 is a bottom view of the outer element of the plant pot assembly of FIG. 1;

(Continued)

FIG. 16 is a top view of the outer element of the plant pot assembly of FIG. 1; and,

FIG. 17 is a top left front perspective view of the outer element of the plant pot assembly of FIG. 1.

Broken lines, where present, illustrate portions of the plant pot assembly that form no part of the claimed design.
